(57) **CLAIM**

The ornamental design for a cord lock with hook, as shown and described.

DESCRIPTION

FIG. 1 is a perspective view of a cord lock with hook showing the new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The broken lines in the drawings represent unclaimed environmental subject matter.
